UNITED STATES PATENT OFFICE.

DAVID C. PRINCE, OF SCHENECTADY, NEW YORK, ASSIGNOR TO GENERAL ELECTRIC COMPANY, A CORPORATION OF NEW YORK.

ELECTRIC-DISCHARGE APPARATUS.

Application filed October 23, 1923. Serial No. 670,372.

My present invention relates to electric discharge apparatus, and more particularly to apparatus of the type in which the useful operating current is carried by means of electrons furnished by a continuously operating ionizing means such for example, as a vapor arc.

Many attempts have been made in the past to provide, in electric discharge devices 10 of the ionization type, control means in the form of grids for controlling the flow of current. Such attempts, however, have not resulted in any intensive use of devices of the type in question, largely, I believe, because of the fact that those constructing such devices have failed to understand all of the phenomena upon which the operation of an ionization device depends and have therefore been unable intelligently to construct a device which would fulfill the operating requirements.

The object of my invention is to provide in an electric discharge device a means for controlling the flow of electrons to a collecting electrode or anode in a desired manner, as, for example, entirely preventing current from flowing to the anode except during predetermined desired intervals.

If an auxiliary electrode of small size be 30 placed in the path of an arc discharge and charged positive a few volts a relatively large current of electrons flows to it from the ionized gas so that it becomes an anode, sharing the current with the main anode. 35 If the electrode be negatively charged, the current to it reverses in direction but only a relatively small current flows, which increases, in general, slowly, if at all, when the negative voltage is raised to several hundred 40 volts. It has now been demonstrated that this current results almost entirely from a flow of positive ions to the electrodes.

Let us now consider the case of a uniformly ionized gas in which there are 45 swarms of electrons and ions moving in random directions with velocities corresponding to a fall of potential of say one volt. Assume that each unit of volume contains equal numbers of positive and negative 50 charges. This is a condition which must always be approximately fulfilled in the positive column.

Then through each square centimeter of an imaginary plane surface there flows a certain current of electrons corresponding to 55 a current density I_L . Similarly, there is a

current density of positive ions which we may denote by I_+ . The ratio between I_L and I_+ is thus the same as the ratio of the velocities of the ions, which is the inverse ratio of the square roots of the masses of the charged particles. Since the mercury ion is 200×1848 times heavier than the electron, we see that I_L is 608 times as great as I_+ .

Instead of an imaginary plane, let us now consider the case of an electrode having a plane surface. If this electrode is electrically insulated and is originally at zero potential (same potential as the surrounding gas) it takes up at first 608 times as many electrons as positive ions, and thus becomes 70 more and more negatively charged, until the number of electrons it receives no longer exceeds the number of positive ions. Under the conditions we have assumed, with electrons having a velocity of 1 volt, the electrode 75 cannot acquire a negative voltage greater than 1 volt, for if it did, it could not receive any electrons at all, although it would continue to receive positive ions.

Let us now assume that the plane electrode be charged to a negative potential of 80 100 volts. Electrons will therefore be prevented from approaching close to the electrode, whereas positive ions will be drawn towards it. There will therefore be a layer 85 of gas near the electrode where there are positive ions, but no electrons, and in this region there will therefore be a positive ion space charge. The outer edge of this sheath of ions will have a potential of -1 90 and the positive ions pass through this outer edge with a velocity corresponding to 2 volts.

Pure electron discharges are well known in which the current is limited by space 95 charge. Between parallel plane electrodes, separated by the distance x , the maximum current I that can flow with the difference of potential V between the electrodes is given by

$$I = \frac{\sqrt{2}}{9\pi} \sqrt{\frac{e}{m}} \frac{V^{3/2}}{x^2} \quad (1)$$

where e is the charge of the electron and m is its mass. If V is expressed in volts, x in centimeters, and I in amperes per square centimeter, this equation becomes

$$I = 2.33 \times 10^{-6} \frac{V^{3/2}}{X^2} \quad (2)$$

100

105

110

Equation 1 is applicable also to currents carried wholly by positive ions if we substitute in the equation the mass of positive ions in place of the mass of the electron. With mercury ions, therefore, the currents given by the space charge equation are 608 times smaller than in the case of corresponding electron currents.

We can now calculate the thickness of the sheath of positive ions in case of any given current density and voltage. For example, let us assume that a plane electrode, charged to a negative potential of 100 volts, takes up a positive ion current of 10 milliamperes per cm.² By substituting these values of I and V in Equation 2, we find x equals 0.020 cm. On the other hand, if the voltage of the electrode were 10 volts, x would be 0.0035 cm.

The thickness of the positive ion sheath with current densities of the order of milliamperes per square centimeter such as those observed in mercury arcs is therefore extremely small; in fact, very small compared with the mean free path of the electrons and ions (2 to 5 cm.). Whether the voltage on the electrode is 10 volts or 100 volts, all the electrons that reach the outer edge of the sheath are reflected back into the ionized gas and all the positive ions that reach this edge of the sheath move towards the electrode and are absorbed by it. The potential of the electrode has no effect on the potential distribution in the ionized gas beyond the edge of the sheath, and since the displacement of the edge of the sheath by changing the potential from 10 to 100 volts is entirely negligible compared to the dimensions of the discharge tube, it is clear that the number of positive ions that reach the edge of the sheath is also independent of the potential on the electrode.

If instead of a plane electrode we have a small cylindrical electrode, the thickness of the sheath of positive ions will vary somewhat with the voltage on the electrodes but even with very high negative voltage will not increase to a value of anywhere near the order of magnitude of the usual diameter of a discharge tube or bulb. The thickness of the sheath also varies with the intensity of ionization. If I_+ is small, the diameter of the sheath will be large, where, if I_+ is large, the diameter of the sheath will be much less.

From the above explanation of the phenomena which are present in the region surrounding an electrode in an ionized gas we are able intelligently to construct a device with a grid which is capable in a practical manner of preventing current from flowing to the anode. Since the sheath of positive ions formed around a grid wire will in any case be of comparatively small diameter, the spacing of the grid wires should be small in order that the sheaths formed around adjacent wires may overlap and thus be capable

of preventing electrons from passing between the grid wires with comparatively small negative voltages on the grid.

Since the thickness of the sheath also is greater the less intense the ionization, the grid will be most effective if located in a region of the device where the ionization is least intense. This will usually be found in a part which is most remote from the source of ionization although the most effective place in this respect for the location of the grid will of course depend to a large degree upon the structure of the device.

Electrons in moving through the ionized gas make elastic collisions with the atoms of gas and hence move in crooked or random paths. As a result there will be nearly as many electrons moving against the potential gradient as with it. Because of this fact it is not sufficient in an ionization device to merely have the grid interposed between the source of ionization and the working anode. The grid must be so arranged that any electrons must pass through the grid in order to reach the working anode whether moving directly toward the anode or in random directions.

In any case, even with fairly large negative potentials on the grid there will be a small number of electrons which because of their high velocity will pass through the grid. If such electrons in reaching the anode have to travel a distance appreciably greater than their mean free path they may produce by ionization of the gas a sufficient number of electrons to permit the current to the working anode to start. The spacing between the grid and working anode therefore should be such that no electrons passing through the grid shall be able to travel a distance appreciably greater than the value of their mean free path before reaching the anode.

These essential requirements may of course be met in numerous ways. I have found that they seem to be met most effectively by placing the ionizing arc in a main bulb and locating the working anode or anodes in a side arm or arms so that the working anode may be located in a region where the ionization is not too intense. The grid also may to advantage be made of fine wire, closely spaced, completely surrounding the anode and comparatively close thereto.

The novel features which I believe to be characteristic of my invention are set forth with particularity in the appended claims. My invention itself, however, both as to its organization and method of operation will best be understood by reference to the following description taken in connection with the accompanying drawing in which Fig. 1 shows diagrammatically the application of a device embodying my invention in a system for converting direct current to alter-

nating; Fig. 2 is an elevation of the grid construction employed in my device, and Fig. 3 is a partial cross-section of the grid and anode construction.

5 I have indicated in Fig. 1 an electric discharge device comprising a main bulb 1 having at the bottom a cathode 2 of mercury with anodes 3 and 4, also of mercury, on either side of the cathode. An arc may be 10 constantly maintained between the cathode 2 and the anodes 3 and 4 by applying between cathode 2 and these anodes an alternating potential from the source 5, the usual reactance 6 being inserted in the lead to the 15 cathode for maintaining the arc. The bulb 1 is provided with side arms 6 and 7. Working anodes 8 and 9 are sealed into the ends of these side arms. Grids 10 closely surround each anode. The anodes may each be 20 sealed into tubes 11. The grid may be of cylindrical form made by winding a grid wire around supports 12, which are secured to a ring 13 surrounding the tube 11. The end of the cylinder adjacent the anode should 25 also be closed by transverse wires. Leads 14 connected to these rings 13 may be sealed into the ends of the side arms 6 and 7 at the same time that the flare 15 on the tube 11 is joined to the end of the side arm. By this 30 expedient there is provided a sufficient distance between the grid seal and anode seal to provide for the high difference of potential between these electrodes existing under certain conditions of operation. A lead 17 35 from the negative terminal of a direct current high voltage source is connected to the cathode 2 and the lead 18 from the positive terminal of the direct current source is connected to the anodes 8 and 9 through an inductance 19 and transformer windings 20 and 21. These windings are shunted by condenser 22 and also by a circuit made up of condensers 23 and a primary 24, which is in inductive relation to a secondary 25, the 40 opposite terminals of which are connected to grids 10. The circuit of the grids is completed from the cathode, grounded at 26, through ground connection 27 and a resistance 28. Alternating current produced by 45 this apparatus may be supplied to a distribution circuit from the secondary winding 29, which is in inductive relation to the windings 20 and 21. The end of tube 11 is constricted at 30 so as to closely surround the 50 insulating shield 31 around the anode lead and exclude electrons from the space 32 surrounding the anode seal. In this way the distance through which electrons traveling in random paths may travel before reaching 55 the anode is greatly reduced.

The manner in which the system operates to produce alternating current is not a part of my present invention, being fully described and claimed in my prior application, 60 Serial No. 599,919, filed November 9, 1922.

It is sufficient to say that I have found that if the grid surrounding either anode is made negative at the instant when the current to the corresponding anode has fallen to zero, current will be prevented from again starting to that anode until the negative potential on the grid has been removed. With the connection shown the grid potentials vary alternately between negative and positive so that when it is desired that current should start to flow to either one of the anodes the grid surrounding that anode is made positive. This grid will then of course receive some electrons, but the current flowing in the grid circuit will be limited by the resistance 28 and the main electron current will flow to the anode.

As an indication of the capabilities of devices operated in accordance with my invention, I have constructed a device similar to that illustrated and having a grid made of 85 10 mil wire spaced 23 mils apart and separated radially from the anode about one quarter of an inch. With this device I am able by impressing a negative voltage on 90 the grid of 130 volts to prevent current to the anode from starting with a positive potential as high as 45,000 volts on the anode.

What I claim as new and desire to secure by Letters Patent of the United States, is:— 95

1. The combination of a receptacle, ionizing means in said receptacle, an electrode in said receptacle for collecting electrons, and a grid electrode substantially surrounding said collecting electrode in the region of 100 minimum ionization, said grid being provided with openings of dimensions to prevent electrons from reaching the collecting electrode when it has positive potentials materially greater than the negative potential 105 of said grid electrode.

2. The combination of a receptacle comprising a side arm, ionizing means in said receptacle, an electrode in said side arm for collecting electrons, and a grid electrode surrounding said collecting electrode in the region of minimum ionization, said grid having conductors spaced from one another distances to prevent electrons from reaching the collecting electrode when it has positive potentials as high as 10,000 volts and when the grid has negative potentials as 110 low as 100 volts.

3. The combination of a receptacle, ionizing means in said receptacle, an electrode in said receptacle for collecting electrons, and a grid electrode in the region of minimum ionization substantially surrounding said electrode and provided with openings of such size with respect to the number of positive ions in the neighborhood of the grid that electrons may be prevented from reaching the collecting electrode with positive potentials as high as 10,000 volts on the collecting electrode and with negative poten- 120 125 130

tial of said grid electrode as low as 100 volts.

4. The combination of a receptacle, ionizing means in said receptacle, an electrode in said receptacle for collecting electrons, a grid electrode in said receptacle surrounding the collecting electrode and comprising 10 mil conductors spaced apart by a distance not substantially greater than 23 mils.
5. The combination of a receptacle, ion-

izing means in said receptacle, an electrode in said receptacle for collecting electrons and a grid substantially surrounding said collecting electrode, said grid being spaced from the anode a distance only substantially as great as the mean free path of said electrons.

In witness whereof, I have hereunto set my hand this 22nd day of October, 1923.

DAVID C. PRINCE.
